FORGING PRESS

Louis F. Carrieri, La Grange Park, and Edwin A. Spanke,
Oak Forest, Ill., assignors to Gulf & Western Manufacturing Company, New York, N.Y.

Filed June 9, 1975, Ser. No. 585,201

Term of patent 14 years

Int. Cl. D15—09

U.S. Cl. D15—123

*Fig. 1.**Fig. 2.**Fig. 3.**Fig. 4*

FIG. 1 is a top plan view of a forging press showing our new design.

FIG. 2 is a left side elevation view thereof.

FIG. 3 is a front elevation view thereof; the rear elevation view being a mirror image in appearance.

FIG. 4 is a right side elevation view thereof.

We claim:

The ornamental design for a forging press, as shown and described.
